BOTTLE OR SIMILAR ARTICLE

Stanley Bindman, Roslyn Heights, N.Y., assignor to Jamison Plastics Corp., North Bellmore, N.Y., a corporation of New York

Filed Oct. 26, 1959, Ser. No. 58,067

Term of patent 14 years

(Cl. D58—6)

Fig. 1 is a front elevational view of a bottle showing my new design;

Fig. 2 is a side elevational view thereof;

Fig. 3 is a top plan view thereof with the cap portion removed.

Fig. 4 is an enlarged fragmentary sectional view taken substantially along the line 4—4 of Fig. 1, and showing the roughening of the portions of the walls of the bottle indicated by stippling in Figs. 1, 2 and 3.

The back of the bottle is the same as the front and the bottom of the bottle is plain.

The dominant features of my design reside in the body portions shown in full lines.

I claim:

The ornamental design for a bottle or similar article, substantially as shown and described.
